UNITED STATES PATENT OFFICE.

HENRY R. NAGLE, OF GRAND RIDGE, ILLINOIS.

AUTOMATIC SWINGING STRAW-STACKER.

SPECIFICATION forming part of Letters Patent No. 431,724, dated July 8, 1890.

Application filed April 16, 1890. Serial No. 348,150. (No model.)

To all whom it may concern:

Be it known that I, HENRY R. NAGLE, a citizen of the United States of America, residing at Grand Ridge, in the county of La Salle 5 and State of Illinois, have invented certain new and useful Improvements in Automatic Swinging Straw-Stackers, of which the following is a specification, reference being had therein to the accompanying drawings, and 10 the letters and figures of reference thereon, forming a part of this specification, in which—

Figure 1 is a horizontal section of the straw-stackers, taken on line 1 of Fig. 2, looking down, showing a plan of the oscillating frame for 15 supporting the straw-carrier and of the devices for oscillating said frame and its carrier and showing the frame supporting the straw-carrier oscillated part way around to show more clearly how it operates; and Fig. 2 is a side 20 elevation of the straw-stackers, showing the position of the carrier in line with the bed-frame.

This invention relates to certain improvements in automatic swinging straw-stackers 25 of the class designed to receive straw from a thrashing-machine and conduct it rearward and discharge it on the top of a stack while swinging or oscillating from side to side, causing the stack to be in a crescent or semicircular form, and is intended to be improvements 30 upon the automatic swinging straw-stackers for which Letters Patent of the United States No. 323,036, of date February 11, 1890, were granted to me; and the said improvements relate, principally, to the mechanism for manipulating and adjusting the straw-carrier to its 35 work.

Referring to the drawings, A represents the bed-frame of the machine, having the cross-beams numbered from 1 to 5, both inclusive, 40 for supporting the working parts of the machine, and said frame is supported on suitable truck-wheels for making the machine portable.

B is a worm-wheel boxed on cross-beam 5. 45 A worm g on shaft S' meshes with worm-wheel B to drive it, and said worm and its shaft are driven by means of drive-belt B' through the medium of sprocket-wheel W', sprocket-chain W², pulley W on shaft a², and a sprocket-wheel 50 on said shaft next said pulley. (Shown in broken lines in Fig. 1.)

D is a circular base boxed at its center on vertical shaft J, upon which it turns and rests at its center on cross-beam 6, supported by cross-beams 1 2 3, and at its outer sides on a 55 suitable number of friction-rollers K, disposed at proper intervals to maintain said base in proper position. Said base D has secured on its upper surface the centrally-located cross-beam E and also the cross-beam F', located at 60 one side of beam D near one side of said base.

S S are beams located, respectively, on and across the outer ends of beams E and E' and properly secured thereto.

Z Z and L L are posts secured, respectively, to the beams S S. 65

H H are arms respectively pivoted near their centers to the side of posts Z Z on a shaft bearing the sprocket-wheel W³. The outer extending ends of said arms support the inner end of the carrier-frame C² by being journaled on a shaft passing through said frame bearing sprocket-wheel W⁴, and their lower inner ends have attached to them the cords or chains i, that connect them to the windlass-shaft a⁶, having the crank, upon which shaft said cords are wound. A ratchet and pawl prevent backward rotation of said crank-shaft. 75

F F are arms having their inner ends respectively pivoted to the posts L L. These arms F F are provided at their outer extending ends with flanged friction-wheels R, upon which wheels R the outer end of the carrier-frame C² rests and moves forward and rearward. 80 The outer ends of the arms F F are supported and elevated and lowered by means of the cords or chains V V, attached to said arms near their outer ends and passing from said point of fastening over pulleys P' P³ to the 90 windlass-shaft a, having the crank a², by means of which windlass-shaft said cords or chains V V may be wound or unwound to elevate and lower the outer end of the carrier-frame C². The carrier-frame C² is provided on 95 its under side with inclined tracks C', upon which the flanged wheels R roll, which prevent the outer end of the carrier-frame from descending while being moved rearward by means of operating-arm H for said purpose. 100

It will be observed that the carrier-frame is supported entirely on the extending outer

ends of the arms H and F and may be elevated and depressed and moved forward or rearward and held in any desired position by said arms, so that they are operated by their cords 5 and windlass mechanism, and that by means of the inclined tracks C' the carrier-frame C² may be moved endwise in a straight line for a considerable distance by the arms H alone without operating arms F. The carrier-belt 10 Y is driven from belt B' on pulley W through the medium of shafts r² J, bevel-gears D' D² D⁶ D⁷, sprocket-wheels r, W³, and W⁴, and sprocket-chains W⁵ W⁶.

The sprocket-wheel W³ is a double-faced 15 wheel for receiving both said sprocket-chains. The oscillating or swing motion is given the carrier-frame by connecting the frame E E' S with the worm-wheel B by means of the pitman g, substantially in the same manner as 20 shown in said patent.

When the machine is not in use and it is desired to transport it, the cord and windlass mechanism may be operated so as to let the carrier-frame C² down, so that its rear end may 25 rest on the notched rests N on the rear end

of the bed-frame and its forward end may rest on the oscillating frame.

Having thus described my invention, what I claim as new, and desire to secure by Letters Patent, is as follows, to wit:

1. In the swinging straw-stacker shown and described, the combination of the oscillating base D, frame E F' S, pitman e, worm g, worm-wheel B, crank C, posts L Z, arms H, arms F, having the flanged friction-wheels R, cords 30 V and i, pulleys P' P³, windlass-shafts a and a⁶, and the carrier-frame C², having the inclined tracks C', substantially as and for the purpose set forth.

2. In the swinging straw-stacker shown and 40 described, the combination of the carrier-frame C², having the inclined tracks C', arms H, arms F, having the flanged friction-wheels R on their outer extending ends, cords i and V, and windlass-shafts a and a⁶, substantially 45 as and for the purpose set forth.

HENRY R. NAGLE.
